CLAIM

We claim the ornamental design for a display screen or portion thereof with transitional graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is the first image of a first embodiment for a display screen or portion thereof with transitional graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the first image of a second embodiment thereof;

FIG. 12 is the second image thereof;

FIG. 13 is the third image thereof;

FIG. 14 is the fourth image thereof;

FIG. 15 is the fifth image thereof;

FIG. 16 is the sixth image thereof;

FIG. 17 is the seventh image thereof;

FIG. 18 is the eighth image thereof;

FIG. 19 is the ninth image thereof; and,

FIG. 20 is the tenth image thereof.

(Continued)

The outermost broken lines show a display screen or portion thereof and forms no part of the claimed design.

The remaining broken lines show portions of the transitional graphical user interface that form no part of the claimed design.

The appearance of the transitional image sequentially transitions between the images shown in FIGS. 1-10 and in FIGS. 11-20. The process or period in which one image transitions to another image forms no part of the claimed design.
